UNITED STATES PATENT OFFICE.

FRANK SPROEHNLE, OF PHILADELPHIA, PENNSYLVANIA.

EXPLOSIVE-ENGINE.

SPECIFICATION forming part of Letters Patent No. 741,179, dated October 13, 1903.

Application filed November 25, 1902. Serial No. 132,712. (No model.)

To all whom it may concern:

Be it known that I, FRANK SPROEHNLE, a citizen of the United States, residing at Philadelphia, in the county of Philadelphia and State of Pennsylvania, have invented certain new and useful Improvements in Explosive-Engines, of which the following is a specification.

My invention relates to improvements in explosive-engines, and has for its object the changing of the size of the compression and explosion chamber by altering the position of the driving-shaft in relation to said chamber. By changing the size of the said chamber I am enabled to alter the power of the engine. By increasing the size of the chamber or cylinder the power is diminished, as the gases are compressed less than the normal amount, and by decreasing the size of the chamber the power is increased as the gases are compressed to more than the normal amount.

A further object of my invention is to advance or retard the operation of the valves and the ignition of the gases to correspond with the alteration of the size of compression-chamber.

Referring to the drawings, Figure 1 represents a plan view of an engine having my improvement embodied therein. Fig. 2 is a vertical sectional view on line 2 2, Fig. 1. Fig. 3 is a view similar to Fig. 2, showing the parts in a different position. Fig. 4 is a vertical sectional view on line 4 4, Fig. 1. Fig. 5 is a horizontal sectional view on line 5 5, Fig. 4, including the bearing and eccentric.

A represents the cylinder of the engine, having the supply-pipe *a* and the exhaust-pipe *a'*, as shown in Figs. 2 and 3.

B and B' are the valves for controlling the supply and the exhaust, respectively.

At either side of the cylinder A are the members C and C', forming the bed of the engine. In these members are formed bearings for disks D and D', which are adapted to rotate in said bearings. Mounted in the disks D and D' is the main driving-shaft E, said shaft being mounted eccentrically in the disks.

A balance-wheel E' is mounted on the shaft E and has a crank-pin *e*, to which is pivoted the connecting-rod F. A crank-arm *e'* supports the outer end of said pin and connects the

same with the driving-shaft E. The connecting-rod F is pivotally connected to the piston-head G.

Mounted on the shaft E is a gear-wheel H, which meshes with a gear-wheel H', having internal teeth, said gear-wheel H' being mounted concentric with the disks D and D', which carry the driving-shaft E.

The gear-wheel H' is provided with a projection to which is secured an annular flange *h*, which is adapted to rotate in a bearing *h'*, secured to the member C. On the periphery of the gear-wheel H' is formed a cam H², which operates the rod I, said rod being provided with a pin *i*, which contacts with the lever J, operating the sparking device J', said rod being also provided with an arm I', projecting immediately in front of the valve-stem *b* of the valve B', controlling the exhaust.

The gear-wheel H' is twice the size of the driving gear-wheel H, and therefore the said driving-shaft will make two revolutions to one of the gear-wheel H'. The piston is drawn forward by turning the shaft E by hand-power, causing a suction and opening the valve B against the action of the spring *b'*. The spring *b* on the valve B' is much heavier, and the valve will not open by means of the suction caused by the movement of the piston.

As the piston is drawn forward the gases are admitted to the chamber A', and as the piston returns the gases are compressed. When said piston reaches its extreme backward position, the cam H² reaches a point where the depression H³ passes the roller *i'* on the rod I, and said rod is given a movement sufficient to cause the pin *i* on said rod to make contact with the sparking device, causing the spark which will explode the compressed gas in the chamber A', which drives the piston G forward with great force. When the piston again returns by means of the balance-wheel, the cam H² has reached a position where the roller *i'* on the rod I will drop into the depression H⁴ in the cam and give said rod a still further movement, which will open the exhaust-valve B' and allow the consumed gas to escape.

The sparking device is constructed in the usual way, the electrical current being admitted to the cylinder through the insulated plug K. A water-jacket A² is also provided

to keep the cylinder cool. This explains the operation of the engine, and my improvements will now be further described and the operation of the same explained.

5 The disks D and D', in which is eccentrically mounted the driving-shaft E, as above described, rotate in bearings formed in the members C and C', said disks being provided with levers D² for rotating them. To insure a simultaneous movement of the disks D and D', the levers are connected by rods d to vertical levers d' and d², pivoted to the bed of the engine. Cross-bars d³ between the vertical levers keep them rigid, and a handle d⁴ is provided for shifting the levers.

10 By rotating the disks D and D' the driving-shaft E may be brought closer to the cylinder, as shown in Fig. 2. This reduces the size of the chamber A', which compresses the gases 20 in a very small space, causing them when ignited to expand very rapidly, giving a high speed and an increase of power to the engine. By rotating the disks to the position shown in Fig. 3 the driving-shaft E is placed farther 25 from the cylinder, the size of the chamber A' is enlarged, and the gases will not be compressed to the extent above described, and therefore the gases when ignited will expand slower and give a slower speed and less power to the 30 engine.

35 When the disks are rotated and the shaft E moved from one position to another, the gear-wheel H upon said shaft will consequently move. The weight of the shaft and balance-wheel will cause sufficient friction to keep the gear-wheel H from revolving. Therefore the larger gear-wheel H' will be rotated in the direction that the disks are being moved. This 40 movement of the gear-wheel H', carrying the cam H², will advance or retard the operation of the rod I, controlling the sparking device and the exhaust-valve.

45 When the shaft E is in the position shown in Fig. 2, the operation of the sparking device and the exhaust-valve will be advanced, and when in the position shown in Fig. 3 the operation of the sparking device and the exhaust-valve will be retarded.

50 Having thus described my invention, I claim and desire to secure by Letters Patent—

55 1. In an explosive-engine, the combination of a cylinder, a piston-head, a movable shaft, and means of changing the size of the compression and explosive chamber by changing the position of said movable shaft, substantially as described.

2. In an explosive-engine, the combination of a driving-shaft, a fixed bearing, a piston-head, a compression and explosion chamber 60 and means of changing the size of said chamber by altering the travel of said piston-head by changing the position of said shaft in relation to the fixed bearing, substantially as described.

3. In an explosive-engine, the combination of a compression and explosion chamber, a driving-shaft, a fixed bearing, a piston-head, a connecting-rod, and means of changing the position of said driving-shaft in relation to the 70 fixed bearing to alter the dimension of said chamber, substantially as described.

4. In an explosive-engine, the combination of a compression and explosion chamber, a driving - shaft, disks rotatably mounted in 75 bearings, said driving - shaft eccentrically mounted in said disks for changing the position of said shaft in relation to said chamber, substantially as described.

5. In an explosive-engine, the combination 80 of a compression and explosion chamber, a driving - shaft, disks having eccentrically mounted therein the said driving-shaft, bearings for said disks, means to rotate said disks to change the size of said chamber, and means 85 of advancing or retarding the operation of a sparking device and an exhaust-valve, substantially as described.

6. In an explosive-engine, the combination of a compression and explosion chamber, a 90 driving - shaft, disks having eccentrically mounted therein the said driving-shaft, bearings for said disks, a gear-wheel on said shaft, a gear-wheel mounted concentric with said disks, a cam on the last-mentioned gear-wheel, and a rod for operating a sparking device and an exhaust-valve, substantially as 95 described.

7. In an explosive-engine, the combination of a compression and explosion chamber, a 100 driving - shaft, disks having eccentrically mounted therein the said driving-shaft, bearings for said disks, levers attached to said disks, connecting-rods, levers pivoted to the bed of the engine, said last-mentioned levers 105 being coupled together, and a handle for operating the same, substantially as described.

In testimony whereof I affix my signature in presence of two witnesses.

FRANK SPROEHNLE.
